UNITED STATES PATENT OFFICE

THOMAS CROPPER, OF ERDINGTON, ENGLAND, ASSIGNOR TO DUNLOP RUBBER COMPANY, LIMITED, OF LONDON, ENGLAND, A BRITISH COMPANY

APPARATUS FOR WINDING ELASTIC STRANDS INTO SPHERICAL MASSES

Application filed December 28, 1928, Serial No. 328,871, and in Great Britain April 4, 1928.

This invention relates to a new or improved apparatus for winding elastic strands and particularly for winding them into or upon cores of golf or other balls.

It has been desired for some considerable time to attain mechanization and automaticity in the performance of apparatus for winding elastic strands for the purpose specified and as the result numerous machines have been devised which operate to varying degrees of success.

In winding the strands it is necessary that they should not follow around a similar course at each convolution, for should they do so the product is not truly spherical which is essential for the purpose for which they are applied. Good results have been obtained from machinery having two horizontal rollers spaced laterally apart, and that have a combined rotary and reciprocating motion imparted to them, the cores nesting between them and being maintained in close frictional contact therewith by pressure rollers that are adapted to contact or impinge upon the cores at the topmost point.

With this type of apparatus however, owing to the peculiar motion imparted to the horizontal rollers, the winding is inclined to follow two definite courses around the surface of the core upon two diameters at right angles to one another. It is known however, that this particular effect can be eliminated by varying intermittently the degree of load imposed by the pressure rollers and to apply it pulsatingly, there being a normal mean pressure and an intermittent pulsation of greater intensity so that upon the increased pressure the cohesion between the core and the rollers increases and the core is restrained in its rotation. Alternatively the pressure may be reduced and the core permitted a period of freedom.

It must be appreciated that in the winding the elastic strand is drawn under tension on to the core from one side thereof and that it is necessary to exert sufficient pressure upon the core to prevent it from being pulled from between the rollers.

Of machines hitherto constructed for performing this class of winding those operated

manually have been the most effective in so far as it would seem that the operator has catered more or less naturally or unknowingly for certain factors which heretofore have not been recognized.

I have found for instance, that as the horizontal rollers are at a constant distance apart from one another, and therefore the core at the commencement of the winding is relatively small, it nests more snugly between them, but as it enlarges it will ride up the surfaces of the rollers and it will rest finally when the desired size has been attained, near the tops of the horizontal rollers. This changing of location of the cores has as a result the diminution of the resistance the horizontal rollers present to the tensioned strand.

I find that another adverse factor to be met with in the winding is that as the mass enlarges the corresponding enlarging of the radius permits a greater leverage to the tensioned strand, this factor together with the decreased resistance of the horizontal rollers combines to remove the core from between the rollers.

The pressure rollers therefore must exert a force sufficient to cater for these exigencies and it has been the practice heretofore to impose a maximum load throughout the winding, but in so doing the pressure at the commencement of the winding is greater than it need be and that it detrimentally affects the winding.

According to this invention means are provided in machines of the kind specified for relatively increasing the degree of load upon the pressure rollers as the mass enlarges during the winding, further means being provided to improve the functioning of the machines as a whole.

In order to render this invention perfectly clear I have appended hereunto drawings illustrating numerous examples wherein:—

Figure 1 is a rear elevation in part section of an embodiment of the apparatus constructed according to this invention.

Figure 2 is an end view in section of the apparatus shown in Fig. 1.

Figure 3 is a further embodiment showing

the piston formed as part of or connected to the pressure rollers supporting spindle.

Figure 4 is a fragmentary sectional view of a further embodiment.

5 Figure 5 illustrates diagrammatically the weight imposing means composed of a series of determinate elements.

Figure 6 is a detail view of a further embodiment.

10 Referring to Figs. 1—2 of the drawings, I provide two horizontally disposed rollers 1 mounted upon spindles 2 with which they have a splined engagement.

The rollers 1 further are acted upon by 15 means that impart to them a longitudinal reciprocating motion, such means in the example shown comprising rollers 3 pivotally mounted upon a bracket 4 upstanding from the base of the machine and engaging cam 20 faces 5 at the ends of the rollers. The spindles are rotated by gears engaged by a gear wheel upon a driving spindle provided upon which are two pulleys one of which is loose.

Pivotally secured to a lever 6 fulcrumed 25 to a bracket 7 secured to the frame of the machine is a bracket 8 which houses within it suitable spindles upon which are mounted rollers 9. These rollers 9 are adapted to impinge upon the top of the core 10 with a force 30 that is greater than that exerted by the weight of the rollers.

To effect the successful winding of the cores it is necessary to produce a pressure upon the cores sufficient to cater for the tension of the strand, and moreover, as previously described, to prevent the winding from following particular courses around the core, it is necessary to vary the amount of pressure, such variations taking the form of an additional greater impulse. To produce this additional impulse, I have provided secured to the lever 6 and through the medium of a link 11 a piston 12 which is housed within a cylinder 13. The piston is influenced by 45 compressed fluid admitted to the cylinder through the pipe 14 and is controlled by a valve 15, the valve 15 having ports or recesses 16—17.

As stated previously, it is necessary to 50 maintain a mean pressure upon the cores throughout the winding, and in an example of the means adapted for this purpose the port 16 in the valve 15 is adapted to be continuously in communication with the cylinder 13 through a port 18.

To produce the greater load a further port 17 in the valve 15 is adapted to communicate with a port 19 in the cylinder 13. Also provided within the cylinder 13 are further ports 20 through which the fluid is exhausted.

As will be appreciated, the valve illustrated is adapted to have imparted to it a rotary motion through the medium of a crank 21 pivoted to a connecting rod 22 which is pivoted at 23 to a crank pin secured to a gear

wheel 24. The gear wheel 24 is driven in any suitable manner, but in the form illustrated takes the drive from a further gear 25 mounted upon one of the spindles 2.

The operation of the apparatus is such that fluid is admitted through the pipe 14 and passes through the port 16 into the cylinder 13 and acts upon the piston 12 to raise it and thus to cause the rollers to press upon the core.

During the rotation of the valve 15 and when the port 17 is in communication with the port 19 more of the fluid admitted through the pipe 14 is allowed to enter the cylinder and to act upon the piston, thereby occasioning a greater pressure. Upon further movement of the valve the port 19 is closed and the fluid prevented from passing therethrough. The greater pressure is rendered intermittent in its application by the continued rotation of the valve.

It is an essential feature of this invention that at least the intermittent greater impulse should increase in extent as the core enlarges during the winding and in the means adopted for this purpose I have provided in the cylinder 13 a series of exhausting ports 20 which are closed successively by the displacement of the piston which, as the core enlarges is forced lower into the cylinder.

I find it desirable however, to provide a further exhausting port 26 which remains operative even when all the ports 20 are closed.

I may if desired produce only the intermittent additional pressure through the medium of fluid pressure and obtain the mean pressure through the medium of a spring or equivalent element acting upon the pressure roller mounting spindle and, in which case the ports 16—18 would be dispensed with, see Fig. 2 of the drawings where the spring is indicated in dotted lines.

Alternatively a spring or weight may be provided to assist in applying the initial mean pressure. As illustrated in Fig. 1 the valve 15 shown is adapted to be rotated, but it must be appreciated that I do not limit myself to any particular construction of such valve, for instance, the valve may be adapted to reciprocate longitudinally, or it may have a combined longitudinal reciprocating and rotary motion imparted to it.

Referring to Fig. 3 the construction shown illustrates a piston 27 secured to or forming part of the pressure roller mounting spindle 28 and moreover in this construction linkage and leverage is dispensed with, the cylinder 29 being connected directly to the frame of the machine.

Also, in this construction the weight of the piston may produce the mean pressure and the fluid admitted through the port 30 controlled by a valve (not shown) would act only to produce the intermittent greater im-

pulses. Further, as shown there are exhausting ports 31 which are successively closed as the core enlarges during the winding.

5 As stated previously, any type of valve may be used and further might be caused to act in any manner other than or as well as rotary. For example in Fig. 4 the valve 32 is adapted to have imparted to it a longitudinal reciprocating motion, this being occasioned in any suitable manner, for instance, as shown diagrammatically through the medium of a lever 33 acted upon by a cam 34.

15 In this construction the valve acts also in the manner of a piston and produces the intermittent greater impulses by the effect of its longitudinal reciprocation.

In operation the fluid directed to the port 35 and passing through the port 36 within the cylinder 37 produces the mean pressure and upon the valve 32 being moved longitudinally the port 35 is closed and the fluid contained within the recess 38 is forced into the cylinder and acts upon the piston in the manner required.

Likewise in this construction exhausting ports are provided for dissipating the pressure and are closed successively by the dis-
30 placing piston.

According to a further embodiment of the apparatus according to this invention the pressure may be produced by determinate weighting elements which, as shown diagrammatically in Fig. 5, comprise a series of members 40 of different sizes or weight and which are freely mounted about an extension 41 of the pressure roller mounting spindle. Normally the elements 40 are spaced away from one another and rest upon shoulders provided within a bearing 43, the position of which is determined in relation to the frame of the machine, and as shown the bearing 43 is adapted to rest upon an abutment 44 upstanding from the frame.

The function of this embodiment is such that as the core enlarges the pressure roller mounting spindle is raised by an abutment or shoulder 45 upon the spindle 41 and engages and lifts the lowermost of the elements 40. Upon the further upward movement of the spindle each of the remaining members 40 are successively imposed until such time that all the elements 40 combine to produce a unitary element.

In order to render the additional imposition intermittent the bearing 43 is raised during such period when only the mean pressure is required and lifts the elements 40 out of engagement with the spindle 41, the movement being occasioned as illustrated diagrammatically in Fig. 5, by a lever 46 fulcrumed at 47 to the frame of the machine acted upon by a cam 48.

66 It must be appreciated that in the embodi-

ment illustrated in Fig. 5 only the greater load is produced by the elements 40, the mean pressure being occasioned by other means, as for instance, by a weight 42 mounted at the top of the spindle 41. Of course, I may utilize other means either in conjunction with the weight 42 or otherwise, to produce the said mean pressure.

Figure 6 shows a further alternative manner of effecting the pressure and shows a spring of the laminated type the leaves 50 of which are spaced away from one another by distance pieces 51 and which are united as a body by bolts 52 to a bracket member 53 that is adapted to be pivotally mounted at 54 to the frame of the machine.

As will readily be seen the pressure roller mounting spindle 55 upon being raised due to the increasing core will tension each of the leaves successively.

To apply the additional pressure intermittently a cam 56 is adapted to act upon a face 57 and to force the bracket and spring downwardly. If desired however, only one leaf may be provided. In this instance either the weight of the spring or an initial tension in it may be relied upon to produce the mean pressure, or alternatively a supplementary spring may be provided.

In constructing apparatus according to this invention the pressure applying means of the kind described need not be supplied with each apparatus, but may be provided at a position or positions remote therefrom and may be adapted to actuate more than one device.

As shown at 59 I may if desired, provide a sleeve which is adapted to control the fluid dissipating orifices in the cylinders.

What I claim is:—

1. In apparatus of the character described comprising horizontal core supporting and rotating rollers, pressure rollers for maintaining a core in close frictional contact with the supporting rollers, a movable support for said pressure rollers and means to impose a constantly acting load pulsatingly upon the pressure rollers to effect intermittently an increased pressure upon the core, the apparatus being arranged so that at least the greater phase of the load applied to the core is increased in magnitude as the core enlarges during the winding.

2. In an apparatus of the character described, a pair of core supporting and rotating rollers, means for moving them axially in opposite directions, pressure rollers mounted for movement toward and from the core supporting rollers, and means for automatically imposing a gradually increasing continuous load upon the pressure rollers as they recede from said supporting rollers. 120 125

3. In an apparatus of the character described, a pair of core supporting and rotating rollers, pressure rollers mounted for 130

movement toward and from said core supporting rollers, and means responsive to movement of the pressure rollers away from said supporting rollers for pulsatingly imposing a gradually increasing continuous load upon said pressure rollers.

4. Apparatus as set forth in claim 1 wherein the means for imposing the load on the pressure rollers are actuated by fluid pressure.

5. Apparatus as set forth in claim 1 wherein determined weighted elements, together with means actuated by fluid pressure are utilized to effect or to assist in effecting the load upon the pressure rollers.

6. Apparatus of the character described comprising a pair of horizontal parallelly disposed core supporting and rotating rollers, means for rotating said rollers in the same direction, means for reciprocating said rollers longitudinally, pressure exerting rollers to act upon a core, supporting means for said pressure rollers, a fluid actuated member for moving said supporting means and a valve controlling said fluid actuated member.

7. Apparatus according to claim 6 and means to actuate automatically said valve for controlling the fluid so as to apply the fluid pressure pulsatingly.

8. Apparatus according to claim 6 including a cylinder having ports for dissipating the fluid, said ports being so arranged that they are closed successively as the core enlarges so as to increase the pressure within the cylinder.

9. Apparatus as set forth in claim 1 wherein only the greater phase of the increasing intermittently applied load is effected by fluid pressure devices.

10. Apparatus according to claim 1 having in combination a pair of horizontally parallelly disposed core supporting rollers rotated by and influenced by means to impart to them a rotary reciprocating motion, said rollers rotating in the same direction and reciprocating longitudinally in opposite directions, pressure rollers mounted for movement towards and away from the horizontal rollers, said pressure rollers being influenced by a force affected extraneous to the weight thereof to maintain the core in frictional contact with said horizontal rollers, said force being produced in part by an elastic member normally imparting a load upon said pressure rollers, said force being further occasioned by fluid pressure acting within a cylinder upon a piston operatively connected to the said pressure roller mounting means, the fluid being admitted to said cylinder through a port which has such movement imparted to it to admit said fluid periodically to produce intermittent impulses, said cylinder having therein exhausting ports to dissipate the pressure, said exhausting

ports being controlled by said piston and close successively automatically with the increasing core.

In witness whereof, I have hereunto signed my name.

THOMAS CROPPER.
